to Allis-Chalmers Manufacturing Company,
Milwaukee, Wis., a corporation of Delaware

Application August 3, 1946, Serial No. 688,233

8 Claims. (Cl. 74—1)

1

This invention relates to reciprocating motors and vibrators, particularly of the type in which a resiliently mounted reciprocable mass element is forced to vibrate relative to a massive reaction support by a periodic force. More particularly the invention concerns reaction supports and resilient mountings for the reciprocable elements of such motors.

In heavy machinery where a machine part having substantial weight is designed to be vibrated at frequencies on the order of twenty-five or more cycles per second at appreciable amplitudes, such as on the order of one to three-sixty-fourths of an inch, the provision of a suitable resilient mounting which will be stable, efficient and durable is a difficult problem.

It is an object of the present invention to provide an improved, simple, durable, resilient mounting arrangement for vibrating elements of reciprocating motors.

Another object concerns an improved arrangement for employment of flat steel disks as spring elements in a resilient mounting for a vibrated machine element.

A more particular object concerns a mounting for disk springs in an improved vibrating system, in which the disks may be readily removed and inserted for tuning, inspection, and replacement.

The above and still further objects which will be apparent from a reading of this specification can best be carried into practical effect as described hereinbelow with reference to the accompanying drawing in which like reference characters indicate the same or similar parts throughout the several views, and in which:

Fig. 1 is a side elevation of a feeder device embodying the present invention;

Fig. 2 is a section of the vibratory motor of Fig. 1 taken on line II—II of Fig. 1;

Fig. 3 is a fragmentary view in section similar to Fig. 2 of a modified form of motor structure;

Fig. 4 is a section of the vibratory motor of Fig. 3 taken on line IV—IV;

Fig. 5 is a detail plan view of a spring disk; and

Fig. 6 is a detail plan view of a modified form of spring disk.

The invention is illustrated in the drawing as embodied in a vibratory feeder in which a feeder pan 1 of conventional type is movably mounted with relation to and may be supported by a massive frame 2. Frame 2 may be suspended by suitable cables 3, or supported in any other suitable known manner, from a base or building structure (not shown). The weight of the pan 1 may be taken on rubber mountings 4 suitably at-

tached to frame 2 or on any other suitable known device providing for relative movement of pan 1 and frame 2. If desired the pan 1 and frame 2 may, of course, be supported independently in movable relation to each other in any known manner (not shown).

An actuating rod or spindle 6 is secured to pan 1, preferably with its axis inclined to the pan floor and passing approximately through the center of gravity of the pan structure. The connection may be, as shown, by a flange 7 detachably secured to a suitable surface on the pan 1, as by bolts 8, or by any other suitable known fastening device.

15 The spindle 6 is preferably provided with a threaded shank portion 9 and a threaded portion 11 of reduced diameter. A clamping nut 12 with an annular clamping shoulder 13 is arranged to threadedly engage shank portion 9, and a yoke piece 14 having an annular clamping surface 16 is arranged to threadedly engage shank portion 11.

20 Spindle 6 is connected with frame 2 by a plurality of annular spring disks 17 arranged in parallel coaxial relation with their center portions 18 clamped between the surface 13 of nut 12 and the surface 16 of yoke 14 in axially fixed, coaxial relation to spindle 6. Peripheral portions 19 of disks 17 are clamped in axially fixed relation between an internal shoulder 21 in a hollow cylindrical spring retaining portion 22 of frame 2 and an annular clamping ring 23, in cylinder 22. The clamping ring 23 may be forced axially toward shoulder 21, as by suitable clamping screws 24 threadedly engaging a suitable internal flange 26 of cylinder 22.

25 The cylindrical spring retaining portion 22 of frame 2 may alternatively be referred to in this specification as an annular spring seat.

30 As shown in the drawing, an axial space is provided between the annular intermediate portions of successive disks 17 as by use of disks having thickened center and peripheral portions 18 and 19. A substantially equivalent alternative construction (not shown) would involve plain flat disks with separate spacer rings between the peripheral and center portions in place of the integral thickened spacer portions 18 and 19.

35 The frame 2 is provided with a part 27 extending transversely across the cylindrical or annular portion 22 and forming a suitable frame for one of the relatively movable parts of a mechanism for applying periodic forces to spindle 6. Preferably this mechanism is constituted by the electromagnets 28 of an electromagnetic

reciprocating motor, the relatively movable armature 29 of which may be connected to yoke piece 14 as by force transmitting rods 31. Armature supporting means, such as leaf spring 32 parallel to and axially spaced from disks 17 may be employed to permit motion of the armature along the main axis of vibration, while preventing lateral deflections. It will be apparent that this leaf spring 32 is only auxiliary to the main spring disks 17 which locate and control the motion of armature 29.

A suitable type of vibrating motor unit is shown in Wurzbach and Kenald, U. S. Patent No. 2,071,-373, and the workings of the electromagnet and armature unit are sufficiently well set forth therein so that no detailed explanation will be required herein as to how periodic forces are produced to move spindle 6 alternately in opposite directions along its longitudinal axis.

The portion 33 of frame 2 provides a mounting surface for rubber mountings 4, and is provided with points of attachment 34 for suspension cables 3.

In the preferred embodiment, shown in Figs. 1 and 2, a peripheral slot 36 is provided in cylindrical portion 22 of frame 2. The purpose of slot 36 is to provide for insertion and withdrawal of the disks 17, such as are shown in detail in Fig. 5. This may be accomplished without complete removal of the pan 1 and spindle 6, by disconnecting spindle 6 from pan 1 and yoke 14 so that it may be axially moved to the position shown in dotted lines in Fig. 2, and inserting or removing disks laterally through the slot 36. The clamping screws 24 and nut 12 are, of course, loosened during the withdrawal and insertion of disks 17.

In the modified form shown in Figs. 3 and 4 disks 17' are constructed according to Fig. 6, with a slot 37 extending radially from the outer periphery to the central opening and having a width at least as great as the diameter of shank portion 9 of spindle 6. Disks of this type may be inserted and withdrawn without disconnecting spindle 6, pan 1 or yoke piece 14, merely by loosening clamp screws 24 and nut 12 and slipping the disks 17' laterally through the slot 36. Disks 17' of course may be rotated during assembly so that the slots 37 may be located in different radial planes when clamped in operative position.

The purpose of the laminated disk spring arrangement is to provide a tunable main spring assembly for a vibrating system which is intended to be operated at or substantially at resonance with the forced impulses. The laminated disk spring of the invention is peculiarly suited to systems involving considerable mass, where straight line vibration is desired, for it provides a very stable mounting with great resistance to lateral displacement in all directions and a high spring rate in deflection of the center portions of the disks along their arcs to either side of a neutral plane. The disks are capable of storing great energies during deflection from neutral in either direction, such stored energies being released during recovery from displacement and imparted to the vibrating element in phase with the driving force. The use of a varied number of disks provides for tuning the natural period of the system to resonance with the predetermined period of forced vibrations applied to the vibrated element.

It will be understood that feeder pan 1 is by way of example only, as any body or mass to be

vibrated may be operatively attached to spindle 6 for vibration thereby, such as vibrating screens and other material treating and conveying devices and vibrating systems to which it may be desirable to convey forceably sustained vibrational movement.

Thus, while specific embodiments of the invention are illustrated and described, the invention will be understood to include all such modifications and equivalents as may be readily apparent to persons skilled in the art to which it appertains, within the scope of the appended claims.

It is claimed and desired to secure by Letters Patent:

1. In a vibrator of the type in which a reciprocable mass is resiliently supported from a frame for vibration along an axis relative thereto, a massive reaction frame having an annular spring retaining portion normal to the axis of vibration, a plurality of parallel coaxially aligned spring disks having their peripheral portions axially fixed in said spring retaining portion, and means connecting said reciprocable mass in fixed relation to the center portions of said disks.
2. In a vibrator, a massive reaction frame having an annular spring seat normal to an axis of reciprocation, a plurality of parallel coaxially aligned spring disks connected in fixed relation to said seat adjacent their peripheral edges, a reciprocable element connected in fixed relation to the central portions of said disks and means for applying periodic forces to said element to reciprocate said element relative to said frame.
3. In a vibrator, a massive reaction frame, a spring retaining cylinder rigidly attached to said frame and having an annular shoulder at one end, a series of spring disks stacked coaxially in said cylinder, clamping means in said cylinder for engaging said series of disks adjacent its periphery to clamp said series of disks axially against said annular shoulder, a reciprocable element connected in fixed relation to the central portions of said disks, whereby said series of disks support said reciprocable element for vibration along their common axis and means for applying periodic reciprocating forces to said element to reciprocate said element relative to said frame.
4. In a vibrator, a massive frame element, a reciprocable element, means for reciprocating said reciprocable element along an axis relative to said frame element, a plurality of parallel coaxially stacked spring disks connecting said elements, said disks having their peripheral portions secured in fixed relation to one of said elements and their central portions secured in fixed relation to the other of said elements.
5. In a vibrator having a massive base element and a reciprocable element, said base element having a hollow cylindrical portion, and said vibrated element having a rod portion extending in coaxially spaced relation through said cylindrical portion of said base element, a peripheral slot in the peripheral wall of said cylindrical portion of said base element, a disk having a radial slot, said disk being insertable through said peripheral slot into coaxial relation with said rod portion within said cylindrical portion, means in said cylindrical portion engageable with peripheral portions of said disk and operable to clamp said peripheral portion of said disk in fixed coaxial relation in said cylindrical portion, means on said rod portion to engage a central portion of said disk in fixed relation, and means to apply periodic forces to said rod portion to

move said rod portion axially relative to said base.

6. In a vibrator, a massive frame having an annulus at one end and a transverse portion spanning the opening of said annulus adjacent one end thereof, a plurality of spring disks in coaxial alinement with and having their edge portions secured in fixed relation in said annulus to form a laminated diaphragm, alined central holes in said disks, a vibrated element having a portion extending through said holes and connected in fixed relation with the disk portions immediately surrounding said holes, and means operatively connected with said transverse portion of said frame and operable to exert periodic forces on said vibratable element to move same axially relative to said frame against the resistance of said laminated diaphragm. 15

7. In a vibrating material handling device, a massive reaction frame, a material treating element resiliently mounted for reciprocatory vibration along an axis of said frame, a rod-like power transmitting member extending along the axis of vibration of said element and attached thereto for vibratory movement therewith, a resilient diaphragm coaxially surrounding said member and having its central portion fixed with relation to said member in supporting relation thereto and its peripheral edges attached in fixed relation to and supported by said massive reaction frame. 30

8. In a vibrator, a massive reaction frame, a resilient diaphragm peripherally secured in fixed relation to and carried by said frame, a power transmitting rod passing coaxially through and carried by the central portion of said diaphragm in fixed relation, said rod being axially movable with relation to said frame by deflection of said diaphragm, means for applying a periodic force to one end of said rod to vibrate the same axially relative to said frame and means to be vibrated attached to said rod on the opposite side of said diaphragm relative to the point of application of said periodic force.
